UNITED STATES PATENT OFFICE

143,232

DESIGN FOR A LAMP OR SIMILAR ARTICLE

Willis Harold Miller, Dallas, Tex.

Application August 19, 1944, Serial No. 114,946

Term of patent 14 years

(Cl. 48—20)

To all whom it may concern:

Be it known that I, Willis Harold Miller, a citizen of the United States, residing at Dallas, in the county of Dallas and State of Texas, have invented a new, original, and ornamental Design for a Lamp or Similar Article, of which the following is a specification, reference being had to the accompanying drawings forming part thereof.

Fig. 1 is a front or face elevational view of a lamp, showing my new design;

Fig. 2 is a side elevational view thereof;

Fig. 3 is a top view thereof.

I claim:

The ornamental design for a lamp or similar article, as shown.

WILLIS HAROLD MILLER.
